AUTOMATIC CHAIN LOCK

Eugene P. Beaumont, New York, N. Y., assignor to Whiting Manufacturing Company, Minneapolis, Minn., a corporation of Minnesota

Application January 14, 1937, Serial No. 120,475

4 Claims. (Cl. 70—93)

The present invention relates to locks, the components of which are permanently mounted on a door and its jamb, and more particularly to the type for effecting a chain connection.

An object of this invention is to provide a novel and improved lock for automatically effecting a chain connection between a door and its jamb, and for automatically removing such connection, by a key-controlled means operative from the outside and also from the inside surfaces of the door, which lock shall embody novel and improved mechanisms to attain a better control of the moving parts, and which lock is an advance with respect to my previous inventions in this type of apparatus identified by my Patent No. 2,075,015 dated March 30, 1937, and my application Serial No. 103,099, filed September the 29th, 1936.

Another object of this invention is to provide in a lock of the type described, a means to maintain the lock structures on both door and jamb in true locus to insure unlocking unfailingly.

A further object of this invention is to provide in a lock offering the aforementioned features, novel and improved means for controlling and actuating the various co-operative mechanisms of the device, in proper timed relation.

Other objects and advantages will become manifest as the disclosure proceeds herein.

In the accompanying drawings, forming part of this application, similar characters of reference indicate corresponding parts in all the views.

Fig. 1 shows a front view of the lock structure which is mounted on the door, including the chain conveying arm.

Fig. 2 is a side view thereof.

Fig. 3 shows the chain member used in this lock.

Fig. 4 shows the cam which controls a latch for securing the free end of the chain to the remote end of the conveying arm.

Fig. 5 shows a front view of the mechanism which is housed within a chamber in the lock structure of Fig. 1.

Fig. 6 is a side view of Fig. 5.

Fig. 7 is a bottom view of Fig. 5, or a right-end view of Fig. 6.

Fig. 8 shows the mechanism in another chamber of the casing of the structure of Fig. 1.

Fig. 9 is a section taken at line 9—9 in Fig. 8.

Fig. 10 is a section taken at line 10—10 in Fig. 8.

Fig. 11 is a section taken at line 11—11 in Fig. 1.

Fig. 12 shows in perspective, the latch element

employed to secure the free end of the chain to the conveying arm.

Fig. 13 is a gage member used in the contrivance.

Fig. 14 is a side view thereof.

Fig. 15 is a ring member used as a collar on the casing.

Fig. 16 is a side view thereof.

Fig. 17 shows the key.

Fig. 18 is a sectional view of a bushing.

Fig. 19 is a side view thereof.

Fig. 20 shows another bushing.

Fig. 21 is a side view thereof.

Fig. 22 is a front view of the keeper adapted to be mounted on the jamb.

Fig. 23 is a left side view thereof.

Fig. 24 is a right side view thereof.

Fig. 25 is a fragmentary view of the casing cover.

Fig. 26 is a side view thereof.

Fig. 27 is similar to that of Fig. 2 having a key-operative cylinder mechanism including a clutch means in open position.

Fig. 28 shows the same with the clutch means in engaged position due to the insertion of the key.

Fig. 29 is a diagrammatic representation showing the complete lock as appearing while the door is unlocked, meaning, free of a chain connection.

Fig. 30 is a similar view, as appearing while the door is locked showing a chain connection between the door and jamb.

Fig. 31 is an "exploded" view showing the components of the clutch mechanism and the key-operative cylinder on which they are mounted.

In the drawings, the chain conveyor arm 130, extends radially outward integrally from the casing cover 131, which caps the cylindrical casing member 132. These parts are held against rotation relative to one another, because the diametrically opposite lugs 133, extending outwardly from the casing member 132, fit into the slots 134 in the casing cover, and these parts are maintained as a unitary structure, by means of the pair of engaging bushings 135 and 136. The wall of the casing member 132, is cut to form element 137, which receives for permanent mounting thereon, the link 138, of the chain 139. At the free end of this chain, is a cross-pin 140, one end of which, indicated by the numeral 141, is adapted to lie within the crotch 142, at the remote end of the conveyor arm 130. A latch 143, slidably mounted on the conveyor arm, extends into the casing 132 to be controlled by the

cam 144, is adapted to secure said cross-pin 140, within said crotch 142.

A plate 145, partitions the casing member 132, into the cylindrical chambers 146 and 147. This 5 plate has a central bore for admission of the bushing 136, and another opening 148, through which extends the cam follower pin 149, from the end of the arm of lever 150, the latter pivoted on pin 151, and controlled by coil spring 152, to maintain the follower pin 149, against the periphery 10 of the latch control cam 144; the bent end 153 of the latch 143, being engaged in the bifurcated bent end of the arm of the lever 150, indicated as 154. To prevent rotation of the bushing 156, it is provided with a socket 155, in the underside of its flange, to set onto the stop prong 156, which is formed out of the metal of the casing 15 cover 131.

The casing member 132, carries the base plate 20 157, a ring 158 having an outwardly extending gage arm 159, and the ring 160; only the latter being fixed thereon by the screw 161, the others being relatively rotatable one to the other. The base plate 157, is adapted to be secured onto the 25 door 70. It is evident that all the components thus far mentioned are assembled to be a unitary structure; there being a flange 162, at the uncapped end of the casing member 132, to journal said member to the base plate 157. The 30 tooth 163, extending from ring 160, is adapted to engage the ring 158, at stops 164 and 165.

The keeper, designated generally by the numeral 166, is adapted to be mounted on the jamb 103. It comprises a base plate 167, and an open 35 casing 168, having an opening 169, in its side nearest the door, to receive the remote end of the gage arm 159, and a crotch opening 170 in its front face, to receive the headed end 171 of the chain's cross pin 140. The crotch opening 170 is 40 arcual, having as its radius, the distance between the axis of the shaft 172, and the axis of the cross pin 140; the former point being the centre of the circle of which it is an arc. The lower portion 173 of the crotch opening is towards the 45 door 70. A spring 174, fixed by pins 175, and the side wall of the keeper casing, extends free within same, and such free arm thereof is normally across the arcual opening 170 of the keeper crotch.

50 A dished sub-base plate 176, has journalled therethrough, the shaft 172, which carries fixed thereon a cam 177, within the hollow 178 thereof at one side, and the gear 179 on the other side of said plate 176. A major segment of a flat, 55 narrow, circular ring, indicated by the numeral 180, is secured onto the sub-base plate 176, concentrically about and spaced from the periphery of the gear 179, only slightly. An internal gear 181, having the stops 197 and 198, on its external 60 periphery, lies concentrically about and slightly spaced from the spacer 180, and is driven by the gear 179, through the pinion 184, which is rotatably mounted on a shaft 185, fixed to and extending from the sub-base plate 176. The latch 65 control cam 144, sits loosely on shaft 172, and is maintained against rotational movement with respect to said shaft, because pinion shaft 185 is received in hole 186. To maintain the assembly of the components carried on the sub-base plate 176, the pinion shaft is slightly riveted over the cam 144. The peripheral diameter of the internal gear 181, meaning its external dimension, substantially equals the internal diameter of the casing 132, with which said gear has slight clearance. The sub-base plate 176, is

5 pinned at 187 to the base plate 157. The shaft 172, lies through the bushings 135 and 136, is rotatable therein, and is provided with a longitudinal key slot 188, to receive the key 189, for operation from the inside surface of the door.

A bolt 190, is slidably mounted and extends through the wall of the dish of the sub-base plate 176, and its movement is controlled by the cam 177, against which its bent end 191, serves as a cam follower, urged by the action of the compression spring 192, one end of which spring is positioned on the fixed pin 193, extending within the hollow 178, of the plate 176. The casing member 132, is provided with a pair of diametrically opposite slots 194 and 195, which are adapted 15 to receive the bolt 190, when shifted therein by action of the cam 177 controlling said bolt. Said casing member 132, also has internally extending lugs 196, lying between the stops 197 and 198, on the external periphery of the internal gear 181, and in the path of such stops. Although only one such lug 196 is essential, two are provided in diametric relation, to attain a more even drive. A socket 199 is provided at the 20 end of the shaft 172, for engagement by the key 25 controlled mechanism.

The cylinder means indicated generally by the numeral 200, is normally wholly independent and without any physical connection with the lock mechanism proper of Fig. 1. I remove the shank 30 of an ordinary cylinder means, and provide the key 189, which fits such cylinder mechanism, with a forward tab 201, adapted to pass through and project outwardly from the shank slot 202 in the end plate 203, which turns with the cylinder. 35 Within a cup 204, having a flanged rim 205 the size of the plate 203, and a shank slot 206 in its bottom, is a headed shank 207 capable of slidable movement therein, carrying the coil spring 208 thereabout. The length of the shank 207, is such 40 that its end 207' lies within the slot 206. This cup 204, with its related components described, is secured to said end plate 203. When the key 189 is inserted in the cylinder mechanism 200, its tab 201, will enter the cup 204, thereby pushing the headed shank 207 into the socket 199 of the shaft 172, to establish mechanical connection with the lock mechanism of Fig. 1.

Upon withdrawal of the key 189, the spring 208, which had been compressed, will shift the headed 50 shank 207 to its initial position, whereby the key-operated cylinder means 200, and the lock mechanism of Fig. 1, are divorced, for said shank will withdraw from its connection with the shaft 172.

When the lock is in unlocked rest condition, as 55 in Fig. 29, the related positions of the components comprising the actuating mechanism is shown in the Figs. 5, 7 and 27, at which time lugs 196 are against stops 197, cam follower 149 is at 209, whereby the cross-pin 140 is secure in the crotch 60 142, and tooth 163 is against stop 164. Now, upon insertion of key 189 into the cylinder mechanism 200, so that connection is made with the shaft 172 as aforesaid, and upon turning said key, whereby said shaft will likewise turn, gear 179 on 65 said shaft, will drive pinion 184, whereupon the internal gear 181, will turn about the spacer 180 as its shaft. At the commencement of this operation, cam 177 will cause the withdrawal of the bolt 190 from casing slot 194, while stop 197 on 70 the internal gear 181 moves away from the casing lug 196, and stop 198 approaches said lug. The casing 132 is now freed of the base plate 176, and upon further rotational movement of the shaft 172, with stop 198 against lug 196, the casing will 75

be turned, the conveying arm 130 will approach the keeper 166, and the headed end 171 of the cross-pin 140 will be conveyed and deposited in the crotch opening 170, whereupon cam follower 149 will reach region 210 of cam 144, and action of the spring 152 will shift said follower so that latch 143 will move to free the cross pin 140 from the conveying arm 130. Upon further rotation of the shaft 172, the arm 130 will be swung to lie as shown in Fig. 30, and shaft 172 having made a complete revolution, the spring 192 will cause bolt 190 to enter the casing slot 195, thereby fixing the casing. Crotch 142 is open, that is free from latch 143. The cross-pin 140 has been drawn into portion 173 of the crotch opening against the spring 174, and the chain 139 is taut. The key 189, may now be withdrawn from the cylinder mechanism 200.

It is to be noted, that during the locking operation, upon movement of the casing 132, tooth 163 moved away from stop 164, whereby ring 158 became loose, and as soon as said tooth reached the stop 165, the gage arm 159 was swung towards the keeper 166, and entered same at 169. The bottom of slot 169, prevents arm 159 from falling further downward, and stop 165 holds it against upward movement. In this way, no planer displacement of the lock structures on door and jamb can occur.

30 The relative number of teeth of shaft gear 179 and the internal gear 181 is such, so that upon one complete revolution of the former, the latter will move an arcual distance equal to the space between the stops 197 and 198, less the width of 35 the casing lug 196, plus a complete half revolution.

To restore the lock to rest open position, the key 189 is turned in reverse direction, whereupon bolt 190 will be withdrawn from the casing slot 195, and then casing lug 196 will approach and contact with stop 197, and it is evident that the 40 operation of all mechanism is exactly in reverse; the cam 144, being so designed, that latch 143 will be shifted to lock the cross pin 140 in crotch 142 at the remote end of the conveying arm 130, as soon as said cross-pin has entered said crotch 142, upon the upward swing of the conveying arm during the unlocking operation. After bolt 190 has receded, the casing 132 is turned, the chain 50 139 loses its tautness, whereupon spring 174 shifts the cross pin 140 in the arcual crotch opening 170, to be intercepted by arm 130 moving upward. Now latch 143, is shifted to lock the free end of the chain to the arm 130 as aforesaid, the 55 gage arm 159 is swung upward because tooth 163 is against stop 164, and the lock structure assumes the initial position, with bolt 190 again in casing slot 194. In rest position, slots 199 and 206 are in alignment.

60 From the inside surface of the door, it is evident that upon insertion of key 189, in slot 188, and by turning the key, shaft 172, will be turned, whereby the lock is operated. To insure that upon withdrawal of the key from said slot 188, 65 that slots 199 and 206 shall be in alignment, the key is provided with notch 209, which becomes engaged on the segmental internal flange segments 210 in the bushing 136, but which is free of said segments, when the key has reached the 70 notches 211, so that it may be withdrawn from

the key-slot 188, when said slots 199 and 206 are in required aligned position.

This invention is capable of numerous forms and various applications without departing from the essential features herein disclosed. It is therefore intended and desired that the embodiment shown herein be deemed illustrative and not restrictive, and that the patent shall cover whatever features of patentable novelty exist in the invention disclosed; reference being had to 10 the following claims rather than to the specific description herein to indicate the scope of the invention.

I claim:

1. In a lock of the type described, the combination of a plate adapted to be mounted on a door, a casing having a radially outwardly extending chain conveying arm, journaled to the plate, a shaft journaled to said plate, extending within the casing, a gear secured on the shaft, and an 15 internal gear mounted within the casing, adapted to be driven by the gear on the shaft; the casing and internal gear being provided with a lug and a pair of stops respectively; said lug being positioned between and adapted to contact said stops 20 successively, whereby upon rotation of the shaft, the internal gear will turn free of the casing for a short interval of time, and upon continued rotation, will engage and turn the casing to swing the chain conveying arm. 30

2. A combination as in claim 1, including a bolt 25 movably mounted on the plate, adapted to engage the casing and fix its position, and a cam mounted on the shaft; said cam being adapted to shift the bolt out of engagement with the casing during the interval the internal gear revolves free within the casing. 35

3. In a lock of the type described, the combination of a plate adapted to be mounted on a door, a casing journaled to the plate, having a radially, 40 outwardly extending chain conveying arm, a chain secured at one end to the casing; said arm being adapted to admit and engage the free end of the chain, a latch slidably mounted on the arm and extending into the casing, adapted to lock 45 the free end of the chain to the arm, a shaft journaled to the plate and extending into the casing, and a cam carried on the shaft; said cam being adapted to control the movement of the latch upon rotation of the shaft. 50

4. In a lock for a door and its jamb, the combination of a chain secured at one end to one of them, a pair of members, each adapted to admit and engage the free end of the chain, mounted on the door and jamb respectively; one fixed and 55 the other pivoted; the free end of the chain being removably engaged in one of said members, a gage arm pivotally mounted with respect to the moving member, adapted to be received by the fixed member, means to swing the first pivoted member whereby the free end of the chain is conveyed to leave the member it had first been in engagement with and to enter and become engaged by the other of said members to effect or remove a chain connection between the door and 60 jamb, and means whereby the gage arm is swung by the first pivoted member in the direction of travel of the latter during the last portion of this travel. 65
